UNITED STATES PATENT OFFICE.

ALFREDO L. ROMERO, OF OAKLAND, CALIFORNIA.

AEROPLANE.

1,257,124.

Specification of Letters Patent. Patented Feb. 19, 1918.

Application filed February 9, 1916. Serial No. 77,275.

To all whom it may concern:

Be it known that I, ALFREDO L. ROMERO, a citizen of the United States, residing at Oakland, in the county of Alameda and State of California, have invented certain new and useful Improvements in Aeroplanes; and I do hereby declare the following to be a full, clear, and exact description of the invention, such as will enable others skilled in the art to which it appertains to, make and use the same.

The invention relates to improvements in aeroplanes.

The object of the present invention is to improve the construction of aeroplanes and to equip the same with means for enabling them to fly with increased speed and to remain stationary in an elevated position or moved rearwardly and also to rise and descend without moving forwardly or backwardly.

A further object of the invention is to provide an aeroplane of this character capable of carrying increased weight and of flying steadily and of maintaining its equilibrium.

Another object of the invention is to provide an aeroplane provided with both driving and lifting propellers and adapted to be simultaneously operated when making a start so as to move upwardly and forwardly with great rapidity and adapted also to be controlled independently of each other whereby the aeroplane may be handled with increased facility.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings

Figure 1 is a side elevation of an aeroplane constructed in accordance with this invention,

Fig. 2 is a plan view of the same partly broken away to illustrate the arrangement of the motors,

Fig. 3 is a front elevation,

Fig. 4 is a horizontal sectional view on the line 4—4 of Fig. 3,

Fig. 5 is a transverse sectional view on the line 5—5 of Fig. 1.

Like numerals of reference designate corresponding parts in the several figures of the drawings.

In the accompanying drawings in which is illustrated the preferred embodiment of the invention, the improvements are shown applied to a biplane but they are equally applicable to aeroplanes of various other types. The biplane comprises in its construction a supporting frame 1 of any desired construction mounted on wheels 2 and supporting upper and lower laterally extending planes 3 and 4. The supporting frame is composed of a lower longitudinally disposed base portion 5 an upright transversely disposed portion 6 and a rearwardly tapered tail portion 7 extending from the center of the transverse portion 6 and carrying dove-tail elevator blades 8 and a vertical rudder blade 9. These blades 8 and 9 are of the usual construction and are controlled in the ordinary manner. The base portion of the frame extends in advance of the transverse portion and mounted on the transverse portion centrally thereof are front and rear rotary combustion engines 10 and 11 having radially arranged cylinders 12 and 13 rotating in vertical transverse planes. These rotary combustion engines which may be of any preferred construction are suitably mounted in the said transverse portion 6 of the supporting frame and the front combustion engine 10 which is preferably a seven cylinder, fifty horse power engine, is provided at the back with a bevel gear 14 arranged vertically and meshing with a horizontally disposed bevel gear 15 of a depending shaft 16. The bevel gear 15 is preferably arranged at a slight inclination and the shaft 16 also has a slight inclination but it may be disposed vertically and it is equipped at its lower end with a lifting propeller 17 having a plurality of blades preferably three as shown. The inclined depending propeller shaft extends downwardly and rearwardly when the aeroplane is in a horizontal position and it is adapted to assume a vertical position when the aeroplane extends upwardly and forwardly at an inclination. The rear combustion engine is preferably a six cylinder, forty horse power engine and it is equipped with a rearwardly extending rotary shaft 18, of a length

to extend in rear of the transverse portion

6 and equipped with a vertically disposed driving propeller 19 rotating within the rearwardly tapered tail portion of the supporting frame and preferably provided with 5 three blades but a guiding propeller of any desired construction may of course be employed.

The frame is provided at the center of the base portion with a rectangular opening 20 extending downwardly from the transverse portion of the frame and forming a passage for the air to enable the lifting propeller to act on the air in elevating the aeroplane. The front and rear motors 10 are adapted to be operated either simultaneously or independently and the aeroplane may be caused to rise without moving forwardly and it may be maintained in a stationary position at an elevation by operating 15 the lifting propeller and stopping the motor of the driving propeller. Also the lifting and driving propellers will enable the aeroplane to be moved rearwardly and it is capable of being driven forwardly and 20 upwardly at an increased speed and the lifting propeller will also enable the aeroplane to carry an increased weight. As the braking and controlling means of the motor are 25 of the ordinary construction illustration 30 thereof is deemed unnecessary and the aeroplane is designed to be equipped with the usual accessories which are omitted for convenience. The location of the rotary combustion engines at the central portion of the 35 frame will increase the stability of the aeroplane and the rotation of the lifting propeller will resist a tendency to tilt and such propeller may be rotated slowly while the driving propeller is operated at a high 40 speed. Also the driving propeller may be rotated at a slow speed while the lifting propeller is driven at sufficient speed to maintain the aeroplane at the desired elevation, the driving propeller serving to maintain 45 the proper position of the aeroplane. In this manner the aeroplane may be main-

tained at an elevation over any desired point in practically a stationary position so that when it is employed for war purposes bombs and other missiles may be dropped 50 with accuracy and arms may also be discharged with accuracy. Also the position of the front and rear engines will enable gasolene tanks 21 and 22 to be located at opposite sides of the center of the aero- 55 plane so as to counter-balance each other. The base portion of the frame has a forwardly tapered front portion or section 23 extending in advance of the transverse portion and preferably carrying the seat 24 for 60 the accommodation of the pilot and the controlling mechanism, not shown.

What is claimed is:—

An aeroplane including a supporting frame having a forwardly tapered front portion and provided with a substantially vertical portion extending upwardly in rear of the said front portion, said frame being also provided with a rearwardly tapered rear portion extending from the said upwardly extending portion at a point above the front portion of the frame, separate front and rear engines mounted in the upper portion of the said upwardly extending portion of the supporting frame, a front propeller shaft depending from the front engine and connected therewith and provided with an approximately horizontal propeller set at a slight angle or inclination to lift the aeroplane and maintain the same in an elevated position, and a horizontal propeller shaft extending rearwardly from the rear engine and having a vertical propeller located back of the upwardly extending portion of the frame. 75 80 85

In testimony whereof I affix my signature in presence of two witnesses.

ALFREDO L. ROMERO.
